AQUARIUM WORM FEEDER

David D. Lovitz, Short Hills, N.J., assignor to Sternco Industries, Inc., Harrison, N.J., a corporation of New Jersey

Filed Mar. 6, 1969, Ser. No. 16,077

Term of patent 14 years

Int. Cl. D30—02

U.S. Cl. D30—12

FIG. 1

FIG. 2

FIG. 3

FIG. 4

FIG. 5

FIG. 1 is a perspective view of an aquarium worm feeder showing my new design.

FIG. 2 is a front view thereof.

FIG. 3 is a side view thereof.

FIG. 4 is a top view thereof.

FIG. 5 is a bottom view thereof.

Both side views are identical and the front and rear views are identical.

I claim:

The ornamental design for an aquarium worm feeder, as shown and described.
